UNITED STATES PATENT OFFICE.

JOHN A. HOFF, OF CHICAGO, ILLINOIS, ASSIGNOR TO PURE CARBONIC COMPANY, OF CHICAGO, ILLINOIS, A CORPORATION OF ILLINOIS.

GAS-VALVE.

1,361,059.

Specification of Letters Patent.

Patented Dec. 7, 1920.

Application filed March 4, 1920. Serial No. 363,340.

To all whom it may concern:

Be it known that I, JOHN A. HOFF, a citizen of the United States, residing at Chicago, in the county of Cook and State of Illinois, have invented certain new and useful Improvements in Gas-Valves, of which the following is a specification.

My invention relates to valves for controlling delivery of fluid under pressure, such for example as the valves used on tanks containing carbonic acid gas approximating a pressure of one thousand pounds to the square inch. I am to provide a simple and easily assembled valve structure wherein gas or other fluid pressure cannot bring about a condition interfering with the working of the valve stem, while at the same time gas pressure is availed of to keep the valve thoroughly packed against any leakage when in use. I furthermore aim to provide a form of coupling in the valve-operating connections which, while permitting the desired axial play of parts in the interests of the self-packing characteristic above mentioned, will at the same time possess exceptional strength so that no matter how hard the valve may turn no breakage of the coupling will occur inside the valve body, and the same is true as to capacity of the coupling to withstand the strain when force is misapplied in a valve-opening direction when the valve is already lifted to the limit or in a valve-closing direction when the valve is already fully seated.

In the drawings which accompany this form part of this specification, Figure 1 represents a longitudinal section of the complete valve structure; Fig. 2 represents a similar section taken at right angles to the Fig. 1 section and showing a different sort of packing; Fig. 3 is a horizontal section taken on the line 3—3 of Fig. 1; Figs. 4 and 5 are perspective views of a piston and coupling member and of the valve plug; and Fig. 6 is a sectional illustration of a modified construction.

The numeral 2 designates the body or casing of the valve structure which has an interior valve-seat 3 and a screw-threaded bore 4 above said valve seat. The numeral 5 designates the valve plug which is screw-threaded to engage said bore and carries a block of aluminum 6 to engage the valve seat. Beyond this screw-threaded bore of the casing there is a smooth bore 7 of an en-

larged diameter in which a piston works, also serving as one member of the valve-operating coupling. The piston is designated by the numeral 8 and it has a conical upper or back portion 9 (Fig. 1) from which extends the stem 10. Packing material 11 is received in the casing above this conical portion of the piston and a screw cap 12 is applied to the casing, the stem of the piston extending loosely through this cap and its squared end-portion being surrounded by a circular flange 12^a on the cap interiorly formed for engagement of a spanner.

The piston is formed with a pair of integral jaws 13 which are of generally segmental shape, and the valve-plug is formed with a cross-head 14 relatively narrow at the middle and widening toward each end. As here shown the opposite sides of this cross-head present arcuate surfaces lying back-to-back, and the jaws of the piston are correspondingly shaped except for being truncated at their middle portions as most clearly shown in Fig. 3. The idea is to employ all the metal possible within the circle of these parts and so dispose it as to supply the greatest strength for the turning of the valve plug by the piston. In this connection it will be noted that the driving contact is confined to the outer thick portions of the cross-head, and it will be obvious that a much stronger coupling is provided than would be the case if a simple flat blade was employed working loosely in a slot.

In putting the parts together it is not necessary to apply any force for the purpose of compressing the packing. The latter can be loosely put in and the screw cap simply turned home, that is until it abuts against the outer end of the casing, the valve-plug having of course been inserted and the piston engaged with it and turned to drive the plug onto the valve-seat. Then when the structure is applied to the tank and the valve is opened, gas will pass through the screw-threads (which engage with some looseness) and enter the piston chamber and heavy pressure will be exerted on the piston with the effect of immediately ramming the packing tight, and the conical formation at the back of the piston will promote the driving of the packing material into intimate contact with the walls of the casing. The packing material not being confined between an internal

shoulder of the casing and a gland and the valve stem with its piston being separate from the valve plug and axially movable relative thereto and the valve-stem-piston being in a chamber to which the gas has access, it is not necessary to rely at all upon the tightening of any gland in order to initially compress the packing. The piston responds instantly to the gas pressure and acts as a ram to compress the packing, and the heavier the pressure the more dense and tighter does the packing become to subserve its function of effectually sealing the valve structure.

15 In my construction packing of loose character (Fig. 1) and of any sort of material that will pack may be employed with good results (I have even found that sand will serve the purpose). However, a satisfactory practice is to employ composition washers such as those that may be found upon the market made of canvas and rubber, and it is desirable to include an ingredient of lubricant such as graphite to guard 25 against so-called "freezing" of the packing to the metal surfaces with which it is in contact. I have shown two such washers in Fig. 2, designated 15. I have also found it desirable to employ a leather washer 16 around the stem under the screw cap, particularly where loose packing is employed, so as to prevent the latter from being forced in between the stem and the walls of the opening in the screw cap. While the conical 35 formation at the back of the piston is advantageous, it is not absolutely essential and when it is not employed and the piston has a flat back surface, a leather washer 17 as shown in Fig. 2 may advantageously be 40 employed here also.

In some instances I may reduce the amount of packing material by employing a single thick fibrous washer backed up by a spring, as shown in the modification illustrated by Fig. 6 wherein the numeral 20 designates such washer, between which and

the flat back surface of the piston a leather washer 21 is interposed. Another leather washer 22 is preferably put behind the fibrous washer. I here preferably employ 50 a flat-metal spring 23 which snugly fits the smooth bore of the casing, bearing at its outer end against the screw cap and at its inner end against a metal washer 24. I may here mention that brass is employed for all 55 of the metal parts of the structure (except merely the seat-block of aluminum) on account of its not being acted upon deleteriously by the gas, and I may here advert to the subject of my novel form of coupling 60 to state that it makes entirely practicable the employment of brass alone notwithstanding its higher ductility and consequent reduced strength for transmitting motion or resisting strain as compared with some 65 other metals. Thus, as before pointed out, I contrive to retain the maximum of bulk in the engaging parts of the coupling and to apply the turning force in such manner as to take full advantage of the maximum 70 thickness of the coating formations which are integral with the respective members between which motion is being transmitted, or resistance encountered.

I claim:

In a valve structure of the character described, a valve screw-plug and a detached stem and piston, the latter and the valve plug having interlocking formations by which to turn the valve plug by the stem 80 while allowing relative axial movement between these parts, said formations comprising a diametrical cross-head on one of said parts thickening from its middle both ways and a pair of jaws on the other part receiving said cross-head between them and being of generally segmental shape complementary to the cross-head, driving engagement between said jaws and the cross-head being confined to the outer thickened portions of the latter.

JOHN A. HOFF.
